UNITED STATES PATENT OFFICE.

HARRY T. KINGSBURY, OF KEENE, NEW HAMPSHIRE.

LOCK FOR TOY SAFES.

1,168,512.

Specification of Letters Patent. Patented Jan. 18, 1916.

Application filed May 9, 1913. Serial No. 766,579.

To all whom it may concern:

Be it known that I, HARRY T. KINGSBURY, a citizen of the United States, residing at Keene, in the county of Cheshire, State of New Hampshire, have invented certain new and useful Improvements in Locks for Toy Safes, of which the following is a description, reference being had to the accompanying drawing, and to the figures of reference marked thereon.

This invention relates to new and useful improvements in locks which are intended for use in connection with toy safes, but which may be used for other purposes with equal success.

The trade has been diligently looking for a cheap and extremely simple lock in which the number of operating parts is reduced to a minimum, and therefore, the principal object of my invention is to provide a lock which will meet these wants.

To this end my invention simply embodies a housing, including a spring locking element, and a key-operated sliding bolt adapted to have locking engagement with said element in either of its extreme positions.

In the accompanying drawings Figure 1 is a rear elevation of a lock constructed in accordance with my invention; Fig. 2 is an enlarged sectional view taken on the line 2—2 of Fig. 1; Fig. 3 is a detail sectional view taken on the line 3—3 of Fig. 1; Fig. 4 is a plan view of the cover plate; Fig. 5 is a plan view of the bolt; and Fig. 6 is a perspective view of the ward plate.

In these drawings I have illustrated one embodiment of my invention and have shown the same applied to a metal door 5, such as, for instance, the door of a toy safe. Attached to the inner face of this door is a housing 6 for a sliding bolt 7. This housing comprises an endless wall 8 which in this instance is formed integral with the door but which may, of course, be formed separate and secured thereto by any suitable means, and a cover plate 9 which is preferably attached to the outer edge of said wall by an interlocking connection, and formed from flat spring steel. This connection consists of lugs 10 which extend laterally from the edge of said wall and fit in corresponding recesses 11 formed in said cover plate. The plate is rigidly secured to the wall by rivets or the like.

Formed in the door or support 5 and communicating with the interior of the housing is a key opening, and disposed in this opening and secured to said support is key-plate seat 12 which receives the usual rotary key-plate 12^a. One edge of the bolt 7 is centrally formed with a gate 13, and when the bolt is in its normal or retracted position, this gate will be in alinement with said key opening.

In order to retain the key-plate 12^a against lateral movement, and also to yieldingly retain the bolt 7 against the cover-plate 9, I have provided a combined spring washer and ward plate 14. This plate 14 is formed from flat spring metal and is provided with outwardly curved fingers 15—15, and laterally extending lugs 16—16. The plate is positioned between the key-plate 12 and the bolt 7, and the fingers 15 bear against the cover-plate 9, the lugs 16 having interlocking connection with certain of the lugs 10 of said wall to retain said key-plate against movement. The plate 14 is also formed with a key-way 17 which registers with the key opening of the door.

In order to lock the bolt in any one of a plurality of positions, I have provided the casing with a spring locking element, and in this instance I have shown this element as consisting of a spring tongue 18 stamped from the body of the cover plate and disposed in a plane at right angles to the line of movement of said bolt. This tongue is formed with an inwardly extending projection 19 which engages in any one of a plurality of seats 20 formed in the adjacent face of the bolt. In the form here shown, the seats 20 are so arranged with respect to the projection 19, that when the bolt is in either of its two positions the projection will engage in one of said seats and thereby frictionally retain the bolt against movement.

From the foregoing it will be seen that I have provided an extremely simple and cheap lock, and while I have only shown one form of the invention, it will be understood that many changes, coming within the scope of the claims, may be made.

Having thus described my invention, what I claim is:

1. In a lock, the combination with a housing including a cover-plate and a bolt slidably mounted in said housing, the cover-plate being provided with a spring tongue

arranged in a plane at right angles to the path of movement of said bolt, said tongue and bolt being relatively formed with a projection and a plurality of seats to frictionally retain said bolt in any one of a plurality of positions.

2. In a lock, the combination with a housing including a cover-plate formed of sheet spring metal and a bolt slidably mounted in the said housing, the cover-plate being stamped with a tongue arranged in a plane at right angles to the path of movement of said bolt, the free end of said tongue and the bolt being relatively formed with a projection and a plurality of seats to frictionally retain said bolt in any one of a plurality of positions.

3. In a lock, the combination with a support, of a key-plate rotatably mounted there-in, a housing attached to said support around said plate, a bolt slidably mounted in said housing, and a combined spring washer and

ward plate disposed between the support and bolt.

4. A combined spring washer and ward plate for locks stamped from spring sheet-metal to provide a keyway and a plurality of curved fingers, said fingers projecting laterally from the same side of the plate. 25

5. In a lock, the combination with a support and a housing, of a bolt slidably mounted therein, the housing being provided with a spring locking element arranged to coöperate with said bolt to lock the latter in any one of a plurality of positions, and a combined spring washer and ward plate disposed between the support and the bolt. 30 35

In testimony whereof, I affix my signature in the presence of two witnesses.

HARRY T. KINGSBURY.
